UNITED STATES PATENT OFFICE.

JAMES E. TUCKER AND AUBREY B. LEECH, OF LOS ANGELES, CALIFORNIA.

ELECTRICALLY-ILLUMINATED DISPLAY DEVICE.

1,192,803.

Specification of Letters Patent. Patented July 25, 1916.

Application filed February 23, 1915. Serial No. 9,792.

To all whom it may concern:

Be it known that we, JAMES E. TUCKER and AUBREY B. LEECH, both citizens of the United States, residing at Los Angeles, in the county of Los Angeles and State of California, have invented new and useful Improvements in Electrically-Illuminated Display Devices, of which the following is a specification.

10 This invention relates to electrically illuminated display devices, and especially to display devices producing pictorial effects by arrangement of shadow parts on an illuminated back ground.

15 It is the object of this invention to provide means for producing thin lines of illumination and shadow.

It is another object to produce a display device in which the lamps used for illumination may be of the uniform bulb size and 20 also have sockets of uniform size.

It is a still further object to provide a display device in which there is a high intensity of light from the illuminated parts.

25 Heretofore translucent walls with relatively opaque parts have been disposed in front of lights. The translucent walls have commonly been glass either transparent or frosted upon which is painted with opaque 30 paints pictorial scenes or characters to be displayed. Such a construction does not permit of a sign which is effective except when the observer is in immediate proximity to the sign, and it is especially ineffective

35 when viewed from the side, and the glass or translucent wall by its absorption of light makes the sign inefficient. Another type of electrical display sign which has been used comprises a plurality of compartments 40 formed by upstanding walls; some of the compartments, being unlighted and thus producing a shadow portion on the sign. This construction does not readily lend itself to the display of thin lines of illumination 45 since compartments in which lights are to be placed may be so small that the lamp ordinarily used with signs cannot be inserted therein, and in order to illuminate the compartment a special lamp must be used.

50 Our improved display device provides an illuminated portion in which the light is not obstructed or absorbed, the rays being directly reflected from the back-ground and thus permitting a high tensity of illumination. It also provides shadow producing 55 portions formed from plates which are

readily cut and are so disposed that light may be projected through thin lines without requiring special lamps.

Referring more particularly to the drawings: Figure 1 discloses a portrait effect secured by our display device. Fig. 2 shows in perspective the silhouette plate 2 of Fig. 1. Fig. 3 is a view in vertical cross section taken on the line 3—3 of Fig. 2. Fig. 4 is a cross section through a compartment taken on the line 4—4 of Fig. 1. Fig. 5 is a view of the pin detail. Fig. 6 is a view showing a perforated plate for obtaining a half-tone effect. Fig. 7 is a fragmentary section as seen on the line 7—7 of Fig. 1.

More specifically an upstanding boundary wall 5 producing the pictorial outline is mounted upon a back ground 12. The wall 5 forms a boundary for the illuminated 75 back-ground. Lights 7 indicated in Fig. 1 by circles are disposed over the surface of the back-ground. These lights are preferably of the usual incandescent lamp style.

Upstanding from the back-ground 12 and 80 secured thereto preferably by rivet heads are pins 8 for supporting the silhouette plates 2. These pins are disposed to offer suitable and secure support for the plates 2. Silhouette plates 2 are opaque and preferably formed 85 of sheet metal. Secured to the silhouette plates and depending therefrom are pins 9 each having a bore 10 for the reception of pins 8, thus forming a telescoping socket connection between the pins 8 and 9. 90

Referring particularly to silhouette plate 2 which forms the shadow for the left eye, a thin line of illumination 11 is shown. If the eye were formed by a walled compartment, it would be difficult to throw light into 95 the recess, and a lamp of special construction would be required for the compartment. By our construction a lamp can be placed immediately under the silhouette plate 2; the reflected light from the back-ground 100 passing through the slit 11. Silhouette plate 18 is shown with a slot 19 and a lamp under said slot of greater diameter than the width of the slot.

The telescoping pin construction permits 105 convenient renewal of lights 7 since the silhouette plate can be slipped off the back-ground pins 8, exposing the lamp and allowing it to be removed from the socket, and a new lamp inserted. The silhouette after 110 renewal of the lamp can be replaced by slipping pins 9 over the pins 8.

To produce half-tone effects the silhouette plate may be perforated as shown by the silhouette 6, the construction being also disclosed in Fig. 6 in which the plate 13 is perforated with holes 14 which permit light to pass through the plate 13, and diminishing the intensity at the spot covered.

Compartments formed by boundary walls may also be used in conjunction with our device. Such a compartment is indicated by 15, and referring more particularly to Fig. 4 it comprises boundary walls 16 and 17, upstanding from the back-ground 12. By using such boundary walls the back-ground within the boundary walls may be cast in shadow. Our construction is also adapted to be used with boundary walls separating the portions of the outline into compartments having back-grounds of different colors.

What we claim is:

1. In an electrical display device, the combination with a back-ground formed to define the outline of a picture, of a plurality of lights distributed thereover, relatively

opaque plates spaced from the back-ground and arranged to conceal a portion only of said lights thereby forming silhouettes to produce pictorial effects, and supporting means for said plates.

2. In an electrical display device, the combination with a back-ground formed to define the outline of a picture, of outstanding pins mounted on said back-ground, a plurality of lights distributed over said back-ground, relatively opaque plates spaced from the back-ground and arranged to conceal a portion only of said lights thereby forming silhouettes to produce pictorial effects, and sleeves secured to said plates and 40 slidingly engaged with said pins.

In witness that we claim the foregoing we have hereunto subscribed our names this 9th day of February, 1915.

J. E. TUCKER.
A. B. LEECH.
